UNITED STATES PATENT OFFICE

2,636,189

TEETHING RAIL

Abraham G. Feldman, Chicago, Ill., assignor to
Storkline Furniture Corporation, Chicago, Ill.,
a corporation of Illinois

Application April 15, 1950, Serial No. 156,070

1 Claim. (Cl. 5—93)

1

My invention relates to teething rails.

In the parlance of the infants' furniture trade, a teething rail is that upper, usually horizontal, bar or edge portion of a side or end wall of a crib or play pen or the like against which a teething infant naturally and instinctively massages its gums and tries out its new teeth both before and after their emergence from the gums.

Objects of my invention are to provide those teething rail improvements herein disclosed and claimed.

A salient feature of a teething rail of my present invention is a sheath, of tough and deformable and resilient material, that is impervious to moisture and externally smooth and free from surface pores and easy to maintain scrupulously clean and sanitary, that is non-splinterable, that is non-breakable in the service it renders, that has no surface coating to be scraped away or scratched by infant teeth, and which clings with remarkable tenacity to the rail part with which it is associated.

Other salient features of a teething rail of my invention are the manners in which the sheath and its associated rail part are inter-engaged and cooperate to retain the former upon the latter snugly and securely.

Important practical advantages of the teething rail of my present invention are that the sheath may be formed of a suitable moldable plastic by an extruding operation, that the sheath may be pressed laterally upon—as distinguished from being slipped endwise upon—its associated rail part, that glue, cement, screws or nails are not essential to the retention of the sheath upon its associated rail part, and that the sheath may be and preferably is a decorative trim part of the crib or play pen or other comparable article of infants' furniture in which the teething rail is incorporated.

The aforementioned and other objects, features and advantages of the teething rail of my invention will more fully and in detail appear from the following description, of a presently preferred embodiment of my invention, in which:

Fig. 1 is a perspective view, partly in transverse section, of a teething rail constructed in accordance with my present invention; and

Fig. 2 is an isolated transverse sectional view of the teething rail sheath as it appears before being applied to the cooperating rail part with which it is to be associated.

Corresponding reference numerals refer to corresponding parts in both figures of the drawing. In Figure 2 the dotted lines indicate the positions to which the several portions of the sheath

are deflected, and from which they tend to recede, when the sheath is appropriately applied to its associated and cooperating teething rail part.

In Figure 1 reference numeral 3 indicates as a whole an upper fragment of a side or end wall or panel of a crib, play pen or comparable article of infants' furniture. The depicted wall 3 comprises the horizontally disposed teething rail part 4, suitably of wood, from which depend the conventional palings 5 for reception by a lower rail (not shown). As thus far described, the structure is or may be quite conventional.

In achieving the objects of my invention, I prefer that the upper portion of the rail part 4 shall be substantially narrower than the lower part thereof and that the rail present upwardly facing longitudinally extending shoulders 6—6 occupying the horizontal plane at which the upper and lower portions of rail 4 merge. Extending longitudinally of the narrower upper portion of rail 4 is an upwardly opening groove or channel 7. Such groove or channel 7 desirably has parallel side walls and is devoid of undercuts of any kind and is located midway between the sides of the rail 4.

At 8 is depicted the teething rail sheath to which previously I have alluded. Such sheath is an elongated member, having the general cross-section of a lazy E with its back up, which suitably is formed, by an extruding operation, of a moldable plastic that is tough, deformable, resilient, impervious to moisture, extremely smooth and free from surface pores, non-splinterable, and substantially non-breakable in teething rail service.

Such sheath 8, which as indicated above should be formed in one piece of a suitable selected moldable plastic, comprises a top or back 9, outer arms 10—10 projecting from the edges of the top or back 9, and an intermediate arm 11. Arm 11 desirably extends the length of the sheath and projects inwardly from the back 9 in the general direction of and midway between the sheath portions 10—10. The length of the intermediate arm 11 in cross section is less than the lengths of the outer arms 10. The outer arms are nearly as long as the back 9.

At its free or inner edge the arm 11 desirably is provided with an enlargement or bead 12 which may be, and preferably is, generally triangular in cross-section.

The top 9 of the sheath desirably is concavo-convex in transverse cross-section; it being the concave surface of the top 9 is on the side thereof from which the arms 10 and 11 extend.

Before application of sheath 8 to rail part 4,

the arms 10-10 of the sheath definitely converge toward each others as they extend away from the sheath back or top 9. The free edges of the legs or arms 10-10 suitably are enlarged at 13-13 as decorative beads which, in the completed teething rail appear as fillets between the plane outer surfaces of the arms or legs 10-10 and the adjacent but offset plane side faces of the lower portion of rail 4.

Sheath 8 readily and securely and satisfactorily is applied and attached to the rail part 4 by forcibly spreading apart the outer arms 10-10 and causing relative lateral, as distinguished from longitudinal, movement of sheath 8 and rail part 4 with the effects that upper portion of the rail 4 is squeezed in the embrace of the sheath, the intermediate arm 11 is embraced by rail 4 with the bead 12 in frictional contact with the parallel walls of the groove or channel 7, and the beads 13-13 lie contiguous with their respective associated rail shoulders 6-6.

The squeeze with which the sheath 8 embraces rail part 4 is substantial and important and is continuously applied because of the resiliency of the plastic material of the sheath and the resultant constant tendencies of the sheath back 9 and the sheath arms or legs 10-10 to re-assume those initial relative positions from which they were deflected upon the assembly of the sheath 8 with the rail part 4. The groove or channel 7 is substantially deeper than the vertical dimension or cross-sectional length of the intermediate arm 11 so that this arm is allowed ample room in which to move downwardly into rail 4 under any severe temporary downward pressure on the sheath back 9.

Having thus illustrated and described a presently preferred embodiment of my invention, which of course is susceptible of modification to meet individual preferences, what I claim as new and desire to secure by Letters Patent of the United States is:

A teething rail for children's furniture and the like comprising, in combination, a rail having a sectional shape characterized by a substantially flat top surface with a groove of substantially rectangular section and deeper than its width ex-

4
tending along the mid-portion thereof, rectangular corners, and opposed marginal recesses extending along the side surfaces at opposite sides of the top surface so as to provide longitudinally extending shoulders facing toward the top of the rail, a sheath of relatively hard and resilient plastic material fitted over the top of the rail and extending therealong to cover the top and side surfaces of the rail down to said shoulders, said sheath having a top wall portion which is normally bowed laterally thereof so that the exterior surface is convexly curved and the interior surface is concavely curved, said sheath also having substantially flat side wall portions integral with opposite sides of the top wall portion and normally converging toward one another away from the top wall portion, and said sheath further having an integral rib extending along the mid-portion of the inner surface of the top wall portion and projecting between the side wall portions, said rib having a wedge-shaped tip thereon and extending therealong, said rail and said sheath being so related in size that when the sheath is mounted on the rail the side wall portions of the sheath abut said shoulders of the rail and assume substantially parallel positions to grip the opposite sides of the top of the rail, said rib on the sheath extending into the groove in the rail and having the wedge-shaped tip thereof firmly gripped therein to hold the sheath in place, and the top wall portion of the sheath remaining somewhat bowed when the sheath is in place on the rail.

ABRAHAM G. FELDMAN.
